UNITED STATES PATENT OFFICE.

DAVID GARFINKLE, OF ALAMEDA, CALIFORNIA.

PRICE-TAG HOLDER.

Application filed August 5, 1924. Serial No. 730,227.

To all whom it may concern:

Be it known that I, DAVID GARFINKLE, a citizen of the United States, and a resident of Alameda, county of Alameda, State of California, have invented a new and useful Price-Tag Holder, of which the following is a specification.

The present invention relates to improvements in price tag holders and has particular reference to convenient means for displaying price tags in front of goods dispensed on shelves arranged one above the other as commonly found in grocery stores or any other stores handling a miscellaneous assembly of goods.

It is particularly proposed to provide means for suspending the price tag relating to goods on one shelf from the next higher shelf, so that the tag itself hangs directly in front of the goods and does not leave any doubt as to the goods to which it is to be applied as distinguished from a card placed on the front edge of the shelf, which creates doubt in the mind of the purchaser or the clerk handling the goods as to whether it applies to the goods on top of the shelf or to the goods placed on the shelf beneath.

It is further proposed to provide as a supporting means for the price tag holder a clamp that may be readily slipped on the edge of the shelf and that is formed with a loop in which the tag holder may be supported. It is further proposed to form the loop and the clamping elements of one single strip of material. It is further proposed to provide a tag holder formed of a single sheet of metal which latter has a curved top adapted to be received in the loop of the supporting element. A further object of the invention is to provide a holder for the tag into which the latter may be easily inserted while the same at the same time offers limited resistance to its removal. Further objects and advantages of my device will appear as the specification proceeds.

The preferred form of my invention is illustrated in the accompanying drawing in which Figure 1 shows a perspective view of my tag holder as suspended from a shelf; Figure 2, a vertical section through the same; Figure 3, a perspective view of the upper section of the tag holder; Figure 4 a plan view of a blank out of which the holder

is formed and Figure 5 a view illustrating a different use of my device. While I have shown only the preferred form of my invention, I wish to have it understood that various changes or modifications may be made within the scope of the claim hereto attached without departing from the spirit of the invention.

My tag holder comprises two principal elements, namely, the clamping device 1, and the holding member 2. The clamping device is made of a single strip of metal 3 bent to present two spaced relatively diverging arms 4 adapted to be clampingly engaged with the front edge of the shelf 6, and a loop 7 formed at the juncture of the lower arm 4 with the body portion of the strip. The said arms 4 are respectively of graduated lengths, one being appreciably shorter than the other so as to facilitate the guiding or application of the clamp to the edge of the shelf. The holder 2 is also made of a single sheet of metal, preferably from the blank shown in Figure 4. A rectangular sheet 8 is provided with a rectangular cut-out 9, through which the tag 11 may be displayed, the same being held in place by means of two lips 12 bent to lie in an adjacent plane parallel to the plane of the sheet and to bear against the rear face of the tag 11. A tongue 13 extends upwardly from the rectangular portion of the sheet and terminates in a small extension 14 which may be curled upon itself in the manner shown in Figure 3 to provide a trunnion adapted to be received in the loop 7 of the clamping member, a recess 16 below the trunnion allowing of the introduction of either arm 4 of the clamping member into the same for engaging the loop with the trunnion.

The whole sheet is provided with a marginal flange 17 for reinforcing the same as well as for offering limited obstruction to the insertion and removal of the tag.

To use my device one of the arms 4 of the clamping member is passed through the recess 16 until the trunnion 14 is brought near the loop 7 whereupon the trunnion is forced into the loop. Thereupon the two arms 4 are made to straddle the shelf from which the tag is to be suspended, preferably the shelf above the one carrying the goods to be marked. The tag, or insert 11, can be

readily inserted and removed although the flange 17 offers sufficient obstruction to prevent accidental dropping out of the insert.

A particular advantage of my arrangement consists in the fact that the same may also be used independently of a shelf. In the latter case the tag in the holder is reversed, the holder is swung upwardly to lie against the short arm 4 of the clamp and 10 the base plate of the clamp may be placed on any suitable support, such as a pile of goods, as illustrated in Figure 5.

When the device is employed as an easel, as shown in Figure 5, the connecting portion 15 of the clamp between the arms 4 of the latter is made to assume a substantially horizontal position where it may rest freely upon packages of goods on a counter, showcase or the like. The short one of the arms 20 4 now extends upward and at a slight rearward angle in order that it constitutes an easel for the price tag holder. Incident to this arrangement the upper portion of the price tag holder, as shown in Figure 5, is 25 at a position to one side of a vertical line

drawn through the loop 7. This gives stability to the structure when in display position.

I claim:

A device of the class described comprising 30 a clamp struck from a single piece of sheet material to provide two relatively diverging arms, a connecting portion between said arms, a loop at the joinder of said connecting portion with one of said arms, the 35 said loop being open at one side, and a tag holding member having a tongue upstruck on itself and rolled to provide a trunnion detachably engaged in the loop and adapted to freely turn therein, and 40 portions formed on the tongue coacting with the ends of the loop to hold the trunnion against longitudinal displacement from the loop, the holding member serving to hang 45 downwardly from the loop when the clamp is adjusted to one position and to extend upward from the loop in an inclined direction and against one of the arms of the clamp when the latter is in another position.

DAVID GARFINKLE.
